US0D1027669S

(12) **United States Design Patent** (10) **Patent No.:** **US D1,027,669 S**
(45) **Date of Patent:** **** May 21, 2024**

(54) **WATCH**

(71) Applicant: **Marco Tedeschi**, Le Vaud (CH)

(72) Inventor: **Marco Tedeschi**, Le Vaud (CH)

(**) Term: **15 Years**

(21) Appl. No.: **35/514,466**

(22) Filed: **May 19, 2022**

(80) **Hague Agreement Data**

Int. Filing Date: **May 19, 2022**

Int. Reg. No.: **DM/221180**

Int. Reg. Date: **May 19, 2022**

Int. Reg. Pub. Date: **Jun. 17, 2022**

(30) **Foreign Application Priority Data**

Dec. 17, 2021 (CH) 146488

(51) **LOC (14) Cl.** **10-02**

(52) **U.S. Cl.**

USPC **D10/32**

(58) **Field of Classification Search**

Primary Examiner — Samantha Wood

(57) **CLAIM**

The ornamental design for a watch, as shown and described.

DESCRIPTION

1. Watch

1.1 : Perspective

1.2 : Perspective

1.3 : Perspective

1.4 : Top

1.5 : Bottom

1.6 : Right

1.7 : Left

1.8 : Front

1.9 : Back

Hatching indicates reflective parts; The broken lines are included for the purpose of illustrating portions of the article and form no part of the claimed design; and view 1.2 shows the winder in open position; view 1.1 and view 1.5 show the winder in closed position.

1 Claim, 9 Drawing Sheets
